UNITED STATES PATENT OFFICE.

MILTON A. FESLER, OF OAKLAND, CALIFORNIA, ASSIGNOR TO PETROLEUM HEAT AND POWER COMPANY, A CORPORATION OF DELAWARE.

LIQUID-FUEL BURNER.

Application filed November 11, 1919. Serial No. 337,176.

To all whom it may concern:

Be it known that I, MILTON A. FESLER, a citizen of the United States, residing at Oakland, in the county of Alameda and 5 State of California, have invented an Improvement in Liquid-Fuel Burners, of which the following description, in connection with the accompanying drawings, is a specification, like characters on the drawings representing like parts.

The invention to be hereinafter described relates to liquid fuel burners, and more particularly to burners in which the liquid fuel is atomized or delivered in spray form 15 by steam or other fluid pressure.

Burners of this type usually comprise steam and fuel passages for conducting the steam and fuel to the delivery end of the burner where they are delivered under the 20 control of a suitable valve. The valve is usually set manually in a predetermined position of adjustment to deliver the quantity of fuel required from the burner. The supply of fuel is regulated by a valve in the 25 fuel feed pipe leading to the burner, and the supply of steam or other fluid is controlled by a valve in the pipe for conducting the same to the burner.

One of the purposes of the present invention is to provide valve means for controlling the delivery of the fuel and steam or fluid from the burner which will be automatically responsive to the pressure of the steam or fluid, and will therefore, automatically regulate the delivery of fuel according to the steam pressure. For example, if the steam pressure is increased, the valve will automatically respond thereto and increase the opening between the 30 valve and its seat and deliver an increased volume of fuel from the burner. On the other hand, if the steam pressure is reduced, the valve will automatically move toward its seat and reduce the amount of fuel delivered, and if the supply of steam is entirely shut off, the valve will automatically close to its seat and prevent the delivery of fuel from the burner.

Another purpose of the invention is to provide a valve device for the burner which will produce a desirable efficient intermingling of the fuel and steam and atomization of the fuel.

Another purpose of the invention is to provide the burner with an orifice for de-

livering the fuel from the burner in transversely curved fan form which will facilitate the efficient introduction of air to the fuel to promote the combustion thereof.

Another purpose of the invention is to provide simple and efficient means for blowing residual fuel from the fuel conducting passage when the burner is to be shut off.

And still another purpose of the invention is to provide a simple, compact, self-contained burner which may be easily constructed and readily operated.

With the aforesaid and other objects in view, the character of the invention will be best understood by reference to the following description of one good form thereof shown in the accompanying drawing, wherein:

Fig. 1 is a vertical longitudinal section through a burner embodying the invention; 75

Fig. 2 on an enlarged scale is a front end view of the burner; and

Fig. 3 on an enlarged scale is a vertical transverse section taken on line 3—3 of Fig. 1. 80

Referring to the drawing, the burner shown therein as embodying the invention, comprises a casing conveniently in the form of a barrel or tube 1 having its rear end threaded into a head 3 provided with a neck 5 for connection with a steam or other fluid supply pipe, and a neck 7 for connection with an oil or other fuel supply pipe. 85

At the front end of the tube or barrel 1 is a head 9 threaded to said tube and containing a delivery chamber 11 provided with an orifice 13 for delivering the fuel from the burner. This orifice may be desirably in the form of an elongated slit curved to deliver the fuel in transversely curved fan form. This slit may have a minimum width midway between the ends thereof, and may widen somewhat toward said ends to compensate for the reduction in pressure on the fuel delivered adjacent the ends of the slit. The construction is such that the fuel will be delivered through said orifice with a transverse curvature forming a pocket which will contribute to the efficient introduction of air to the atomized fuel. In 105 other words, when air is directed transversely toward the path of the fuel, the transversely curved character of the fuel will tend to pocket the air and facilitate the control of the mixture of air with the fuel. 110

Within the tube or barrel 1 is an oil or other fuel conducting passage conveniently afforded by a tube 15 having its rear end ⁵ threaded to an elbow 17 in the head 3 referred to, and communicating with the oil or fuel supply neck 7. The inner tube projects toward the delivery head 9, and is spaced sufficiently from the tube 1 to leave an ample steam conducting passage 19. Lugs 21 may ¹⁰ be interposed between the fuel and steam conducting tubes to contribute to the proper centering of the fuel tube in the steam tube.

Suitable valve means may be provided for controlling the discharge of the fuel and steam from the fuel and steam conducting passages into the delivery head. This valve means, in the present instance of the invention, comprises a single conical valve 23 co-operating with seats afforded by bushings ¹⁵ 25 and 27 fitted into the steam conducting tube and the fuel conducting tube respectively. Suitable means may be provided to automatically close said valve to said seats, but allow the valve to open in response to the ²⁰ pressure of the steam or other fluid thereon. This means, in the present instance, comprises a stem 29 threaded or otherwise secured to the valve and projecting rearward through the fuel conducting tube 15, and ²⁵ thence through the elbow 17 and the rear end of the head 3, where it receives a coil spring 31 confined between an end of said head and a washer 33 secured by an adjusting nut 35 and a lock nut 37. The spring ³⁰ may be enclosed by a cap 41 screwed onto a neck 43 projecting rearwardly from the head 3. The construction is such that the spring will tend to shift the stem 29 rearwardly and move the valve 23 to the seats 25 and 27, but ³⁵ when steam is admitted to the steam passage, the spring will yield under the pressure thereon and allow the valve to move from its seats, and the amount of fuel delivered will be proportional to the pressure of the steam. ⁴⁰

The fuel and steam will flow through the annular passage thus afforded by the opening of the valve, and will be desirably mixed and intermingled with efficient atomizing effect on the fuel on flow thereof past the rather ⁴⁵ sharp front end of the conical valve. The head may have an inturned flange 45 adjacent the valve, which will tend to direct the fuel and steam inwardly of the delivery chamber 11, and thereby further contribute ⁵⁰ to the intermingling thereof, and the efficient atomization of the fuel.

The cap 41 may be readily removed to furnish convenient access to the nuts 35 and 37 to permit the tension of the coil spring 31 ⁵⁵ to be varied according to conditions as desired.

Suitable means may be provided to enable the steam to blow out residual fuel from the tube 15 when the burner is to be shut off. To ⁶⁰ accomplish this, in the present instance, the

elbow 17 referred to, may be provided with a port 47 (Fig. 3) having a tapered seat 49 co-operating with a needle valve 51 on a stem 53 having a portion 55 threaded in a sleeve 57 screwed into a neck 59 projecting ⁷⁰ from the head 3. To prevent leakage past the stem 53, suitable packing 61 may be confined between the end of the sleeve 57 and a cap 63 threaded to said sleeve. The outer end of the needle valve stem 53 may be provided with a suitable handle 65. The construction is such that the handle may be rotated to withdraw the needle valve 51 from the seat 49, thereby admitting steam from the chamber surrounding the elbow 17 ⁷⁵ through the port 47 into the tube 15 to blow out any residual fuel therefrom.

In use, on admission of the fuel and steam or other fluid into the fluid and steam passages respectively, the valve 23 will respond ⁸⁰ to the pressure thereof and automatically move from its seats, thereby allowing flow of the fuel and fluid into the chamber in the delivery head 9 and the delivery thereof from said chamber through the orifice 13. ⁸⁵ The valve will automatically respond to the pressure, and allow a greater or less amount of fuel to be delivered from the burner in proportion to the pressure. When the supply of steam is shut off, the coil spring 31 ⁹⁰ will automatically close the valve to its seat.

By my invention there is provided a simple, compact, self-contained burner which may be readily operated and controlled as desired, and a burner which will efficiently ¹⁰⁰ mix the steam or fluid with the fuel and thoroughly atomize the latter.

It will be understood that the invention is not limited to the specific embodiment shown, and that various deviations may be ¹⁰⁵ made therefrom without departing from the spirit and scope of the appended claims.

What is claimed is:—

1. A liquid fuel burner, comprising, in combination, a steam conducting tube, an oil conducting tube mounted in said steam conducting tube, a delivery head communicating with said tubes, a single valve for automatically controlling the discharge of steam and oil from said tubes into said head, a stem for said valve projecting through the oil conducting tube, and a coil spring co-operating with said stem to close said valve, but yieldable in response to steam pressure on the valve to allow the latter to open. ¹¹⁰

2. A liquid fuel burner, comprising, in combination, a steam conducting tube, a head connected to said tube having necks for connection with steam and oil supply pipes, an elbow mounted in said head and communicating with said oil supply neck, an oil conducting tube mounted in said steam conducting tube and connected with said elbow, a delivery head connected to said steam conducting tube, a single valve at the delivery ¹¹⁵ ¹²⁰ ¹²⁵ ¹³⁰

end of said tubes and co-operating with each of the tubes to control the discharge of the steam and oil from their respective tubes into said delivery head, and means including a spring tending to close said valve, but allowing the latter to open in response to steam pressure thereon.

3. A liquid fuel burner, comprising, in combination, a casing having concentric oil and steam conducting passages therein and provided with a delivery head, a single valve for controlling the discharge of both the oil and steam from their respective passages, a stem projecting from the valve through one of the passages beyond said casing, a spring adjustably secured to said stem to urge the valve to closed position, and a cap for the spring detachably connected to the casing to allow ready access to the spring.

20 4. A liquid fuel burner, comprising, in combination, a casing having an end provided with a delivery orifice, a fuel conducting tube mounted in said casing and spaced therefrom to provide a fluid conducting passage between said tube and casing and surrounding the tube, a single valve mounted in said casing and in the path of travel of the fuel and fluid for controlling the discharge of both the fuel and fluid from the casing, a member connected to said valve and projecting rearwardly beyond said casing, and a spring co-operating with said member tending to move said valve to closed position, but yieldable in response to the pressure of the fluid upon the valve to allow said valve to open.

5. A liquid fuel burner, comprising, in combination, a casing having a delivery end and provided with fuel and fluid conducting passages leading to said delivery end, said passages having separate valve seats at their delivery ends, a single valve cooperating with both of said seats to control the delivery of fuel and fluid from said passages to said delivery end, said valve being movable to open position in response to the pressure of the fluid thereon, and means for automatically closing said valve to interrupt the delivery of fuel and fluid when the supply thereof is shut off.

6. A liquid fuel burner, comprising, in combination, a casing having a fuel conducting tube therein and spaced therefrom to leave a fluid conducting passage, a single valve for controlling the discharge of both the fuel and fluid from said tube and passage respectively, spring means tending constantly to close said valve, said tube having a port communicating with said passage, and a valve adapted to be opened to admit fluid from said passage into said tube to blow residual fuel from the latter.

7. A liquid fuel burner, comprising, in combination, a casing having a valve seat therein, a fuel conducting tube mounted in

said casing having a valve seat and spaced from said casing to provide a fluid conducting passage between the tube and casing, a single valve co-operating with both of said seats to control the discharge of the fuel and fluid from the casing, and spring means tending to move said valve toward said seats to interrupt the flow of fuel and fluid from the casing, and yieldable in response to pressure of the fluid on the valve to allow the latter to open.

8. A liquid fuel burner comprising, in combination, a casing provided with fuel and fluid passages having their discharge ends adjacent each other, a single valve engaging the discharge ends of both of the passages and operable to control the discharge of fuel and fluid from said ends, and means for yieldingly retaining said valve in its closed position and allowing the valve to open automatically in response to the fluid pressure upon it a distance proportional to said pressure.

9. A liquid fuel burner comprising, in combination, an inner tube having a passage-way therethrough, an outer tube surrounding the inner tube and having a passage-way between the inner and outer tubes, connections for delivering fuel to one of the passage-ways and fluid to the other passage-way, each of said tubes having a valve seat at the delivery end thereof, a single valve co-operating with each of said seats, a stem connected to said valve and extending therefrom through the inner tube, and a spring acting upon the stem and tending constantly to force the valve into closing engagement with said seats, but yieldable in response to the pressure of said fluid upon the valve to open the valve and allow discharge of the fuel and fluid from the burner.

10. A liquid fuel burner, comprising, in combination, a casing provided with fuel and fluid conducting passages, having discharge openings provided with independent valve seats, a single valve cooperating with both of said seats to control the discharge of both the fuel and fluid from the respective openings, and spring means tending constantly to close said valve, but yieldable in response to the pressure of the fuel or fluid to open and allow discharge of the fuel and fluid between the valve and said seats.

11. A liquid fuel burner, comprising, in combination, a casing provided with an inner fuel conducting tube and a steam conducting tube surrounding the inner tube to heat the fuel within the inner tube, said tubes having independent valve seats, and a valve cooperating with both of said seats for controlling the discharge of fuel and steam from said tubes.

12. In a fuel oil burner, the combination of a casing having separate oil and atomizing fluid conducting passages therein, valve

means for controlling the delivery of oil and atomizing fluid from said passages, said valve means being movable to open by and proportionally to the volume of atomizing fluid passing therethrough and to admit oil by said opening movement in proportion to the volume of atomized fluid admitted, and spring means automatically to reduce the valve opening on reduction in the volume of 10 atomizing fluid passing therethrough.

13. In a fuel oil burner, the combination of a casing, passages for conducting oil and steam thereto, one of said passages encircling

the other, a valve seat adjacent the delivery ends of said passages, valve means cooperating with said seat to control the flow of oil and steam, and spring means tending to move said valve means toward its seat, said valve means having a surface subject to the pressure of the flow of steam through the 20 steam passage to move said valve means away from its seat against the resistance of said spring means.

In testimony whereof, I have signed my name to this specification.

MILTON A. FESLER.
